THOMAS W. CAPEN, OF MILWAUKEE, WISCONSIN, ASSIGNEE TO ALLIS-CHALMERS COMPANY, OF MILWAUKEE, WISCONSIN, A CORPORATION OF NEW JERSEY.

TUBE-MILL LINING.

1,053,084.

Specification of Letters Patent. Patented Feb. 11, 1913.

Application filed December 2, 1910. Serial No. 595,182.

To all whom it may concern:

Be it known that I, THOMAS W. CAPEN, a citizen of the United States, residing at Milwaukee, in the county of Milwaukee and 5 State of Wisconsin, have invented a certain new and useful Improvement in Tube-Mill Linings, of which the following is a specification.

This invention relates to improvements 10 in the construction of linings for tube mills such as are used for grinding various materials.

The object of the invention is to provide 15 a tube mill lining which is simple in construction and in which the use of fastening means, such as bolts exposed to the interior of the mill, is entirely avoided.

In fastening the linings to the interior of tube mills with bolts or similar means having their clamping portions exposed to the grinding surfaces, it has been found that the clamping portions after a time wear off, resulting in loosening of the lining and possible wrecking of the mill. With the construction of a lining in accordance with the 25 present invention the lining fastening means is not exposed to the grinding surface of the mill in such a way that the deterioration would have the effect of loosening the lining. The use of through bolts as a fastening means is furthermore objectionable in that dust is permitted to escape from the interior of the mill along the bolt surfaces.

30 A clear conception of an embodiment of the invention can be obtained by referring to the accompanying drawing in which like reference characters designate the same or similar parts.

40 Figure 1 is an elevation, partly in section, of a tube mill having a boltless lining applied, showing also fragments of the mill supporting piers. Fig. 2 is a development of several sections of drum lining similar to 45 that applied in the mill shown in Fig. 1. Fig. 3 is a vertical transverse section through a tube mill as shown in Fig. 1, the section being taken along the line III—III of Fig. 1 looking in the direction of the arrow. Fig.

50 4 is an enlarged fragmentary central vertical section of the discharge end trunnion and liner therefor, of the device shown in Fig. 1.

55 The tube mill shell or drum, see Fig. 1, is provided with suitable manholes 3, only

one of which is shown, for permitting inspection of the interior of the mill and for insertion of the lining. The feed end head 5 incloses the feed end of the mill drum 1, and has an outwardly projecting trunnion 60 supported in a suitable bearing mounted on the top of a supporting pier 11. The discharge end head 18 incloses the discharge end of the drum 1 and has an outwardly projecting trunnion supported in a bearing 65 mounted on a second supporting pier 11. Caps 10 inclose the upper halves of the trunnions and prevent grit from injuring the bearings. The driving gear 4 is formed in one with, or is rigidly connected to, the 70 drum 1 and receives its driving power from any suitable source, not shown.

The interior of the drum 1, see Figs. 1, 2 and 3, is lined with a series of wedge shaped liner sections 2 having their opposite edges mutually tapered and normal to the lining surface. In the construction shown, see Figs. 1, 2 and 3, the liner sections 2 are formed in rings of four sections each, around the interior periphery of the 80 drum 1. The sections 2 are held in position by means of a tongue 22 formed at the end of one section and coacting in a groove 23 formed in the end of the next adjacent section. Each of the sections 2, as shown in 85 Fig. 2, is provided with a tongue on one end thereof and a groove on the opposite end thereof, but the sections 2 may be formed with the tongue on each end of one section and a groove on each end of the 90 next adjacent sections, as shown in Fig. 3. Section 20, see Fig. 2, is formed in two parts, the two parts being spread apart and retained in position by the insertion of 95 shims 19. The shims 19 may be omitted, shell section 20 be formed in one piece and the retaining means be effected by shims 21, as shown diagrammatically in Fig. 2, such construction avoiding the forming of a shell 100 section in a plurality of parts. The use of shims obviates the necessity of accurate fitting of the sections.

The feed and discharge end heads 5, 18, are lined with a plurality of segmental end liners 6 which are held rigid against the 105 end heads at their outer ends by the shell sections 2 lining the drum 1, and at their inner ends by the feed and discharge trunnion liners 17, 15, respectively. The end liners 6 are formed with tongues 7 extend-

ing radially from the center of the mill and coacting in grooves 8 formed in adjacent end liners 6. It will be noted that the diameter of the end liners is slightly less than that of the interior of the drum 1, thus leaving an annular space around the periphery of the end liners. This space is normally filled with cement or other suitable material which prevents the liner 6 from 10 radial displacement away from the center of the drum 1.

The feed trunnion liner 17 coacts against the feed head liners 6 along a conical surface, the largest diameter of which is exposed to the interior of the mill drum 1. The feed end clamping bushing 9 has hook shaped projections 12, preferably two in number, which extend into recesses 13 formed in the outer end of the feed trunnion liner 17. These hook shaped projections 12 are of such a width and shape that they can be first inserted longitudinally into the recesses 13 of the liner 17, after which they permit a partial rotation of the clamping bushing 9 by means of a wrench inserted in the notches 14.

The discharge trunnion liner 15 is provided with the usual discharge screen, see Fig. 4, and coacts with the discharge end head liner 6 along a conical surface having its greatest diameter toward the interior of the mill drum 1. The discharge clamping bushing 16 has hook shaped projections 12 extending into recesses 13 of the liner 15 in a manner similar to the arrangement of these elements at the feed end of the mill.

In lining the tube mill the lining is first applied to the end heads and trunnions. The sections or liners 6 are admitted to the interior of the mill through the manholes 3 which should be of sufficient dimensions to permit insertion of all sections of the lining, and are set in position against the end heads 5, 18. By forming the outer diameter of the end liners 6 slightly less than the inner diameter of the drum 1, the insertion and removal of the last liner 6 of a set or series is easily permitted. After the liners 6 have been assembled, the trunnion liners 17, 15, 50 are inserted from the interior of the drum 1. The clamping bushings 9, 16, are then inserted from the exterior of the mill and are given a partial rotation causing the ends of the hooks 12 to coact along surfaces 24 formed in the recesses 13 of the trunnion liner 17, 15. The surfaces 24 are inclined so that as the hooks 12 are forced forward a rigid locking of the clamping bushings and trunnion liners is effected. The unfilled 60 portion of the recesses 13 are then filled with liners or shims, to prevent the hooks 12 from backing up. With the end head and trunnion liners in place, the shell sections 2 are wedged together along the inner surface of 85 the drum 1 as shown in Figs. 1, 2, 3. The

procedure in lining the interior of the drum 1 is to begin at either the feed or discharge end head liners, rings or series of sections 2 being inserted until the opposite end head liner is reached. In placing the last series of shell sections 2, three of the sections are first inserted, there being nothing unusual preventing such insertion. The fourth section of the last series could, however, not be inserted since the end head of the mill would prevent longitudinal shifting of such last section. The section 20 is therefore formed in two parts, the portions forming the shell section 20 being inserted coacting along the drum surface, after which they are spread circumferentially, being fixed in this position by the insertion of liners or shims 19. 75

With this construction of lining, it will be noted, that there are no objectionable through bolts and no portion of the fastening means for the liners is exposed to the interior wearing surfaces of the mill, thus avoiding the undesirable feature of having the fastening or clamping means for the liners worn away by the abrasion of the material being ground, and eventual loosening of the lining. 90

In actual construction of the lining, corrugations or projections are formed extending longitudinally or circumferentially of the drum 1, but these have been omitted from the disclosure in the drawing since a showing of same would only tend to detract from the clearness of the disclosure. These corrugations or projections on the lining are 100 for the purpose of permitting pebbles to lodge in the lining thereby forming an automatic protecting lining. 95

It should be understood that it is not desired to be limited to the exact details of 105 construction shown and described, for obvious modifications will occur to a person skilled in the art.

It is claimed and desired to secure by Letters Patent,— 110

1. In a tube mill, a drum, a lining for said drum, consisting of a series of portions, a plurality of wedge shaped sections comprising one of said portions, said sections having tongues and grooves on opposite edges thereof, and means for advancing one of said sections along the surface of said drum to secure said sections in place, said means lying entirely within said drum. 115

2. In a tube mill, a drum, a lining for said drum consisting of a series of portions, a plurality of sections constituting each of said portions, said sections having edges normal to said lining surface and having opposite edges mutually tapered, and means for advancing one of said sections along the surface of said drum to secure said sections in place, said means lying entirely within said drum. 120

3. In a tube mill lining, a plurality of 125

segmental sections having interlocking adjacent edges and forming a disk, a bushing concentric with said disk, a drum surrounding said disk, and a drum lining abutting the edge of the face of said disk, said bushing and sections being formed for preventing displacement of said disk relative to said drum.

4. In a tube mill lining, a trunnion lining bushing, and a clamping bushing placed end to end with said trunnion lining bushing and interlocking therewith to secure said lining bushing in place within said trunnion.
5. In a tube mill, a cylindrical drum, and a lining for said drum, said lining compris-

ing a plurality of wedge shaped sections having tongues and grooves on opposite edges thereof, means for advancing at least one of said sections along the surface of said drum to produce registration of the tongues of some of the sections with the grooves of adjacent sections, and means for locking said sections in place, said locking means lying entirely within said drum.

In testimony whereof, I affix my signature in the presence of two witnesses.

THOMAS W. CAPEN.
